WICK TYPE OIL BURNER CONTROL

Harry C. Shagaloff, Evansville, Ind., assignor to
Servel, Inc., New York, N. Y., a corporation of
Delaware

Application May 15, 1941, Serial No. 393,687

5 Claims. (Cl. 158—94)

This invention relates to a wick type oil burner, and more particularly to an improved wick type burner structure which affords better adjustment and control of the burner flame.

That which is new in the subject burner, and which constitutes the invention, is a new operative relationship of parts. An annular wick holder contains a cylindrical wick and is provided with a known turner for moving the wick up or down in the holder to adjust the exposure of the wick at the upper edge of the holder. The holder and its wick and the turner comprise an assembly located in and movable up and down in an annular space between an inner chimney and an outer chimney. These chimneys are provided with perforations to supply air to a combustion zone in the upper part of the annular space between the chimneys. Thermostatically operated mechanism is provided to move the wick and holder assembly up and down relative to the chimneys to regulate the heat of the burner flame.

The burner structure is explained in detail in the following description which should be considered in connection with the accompanying drawings of which:

Fig. 1 is a perspective view of a burner embodying the invention, portions being cut away to better show the details of construction;

Fig. 2 is a sectional view on line 2—2 of Fig. 3; and

Fig. 3 is a sectional view on line 3—3 of Fig. 2. Referring to Fig. 1 of the drawings, a burner 22 is provided with a frame structure formed by: a casting 156, indicated at right center; a base plate 158 which is mounted on the casting 156 and which is provided with a rim 160; an upper flanged ring 162; and a cylindrical perforated cover 164 mounted between the rim 160 and the upper ring 162. The perforated cylinder 164 forms the lower portion of a stationary outer chimney assembly 112 to be further described. As best seen in Fig. 3, the cover 164 has end portions 165 which are joined to the two sides of the casting 156. The base plate 158 has a central disc portion 166 connected to the outer portion of the base plate by four radial strips 170. The disc 166 and the strips 170 are formed by cutting four arcuate holes 171 in the base plate.

The flanged ring 162 (Fig. 1) is provided with a flange 180 which has a down turned rim 182. A truncated cone 184 is supported on the flange 180. The cone 184 has a cylindrical chimney portion 186, the upper end of which has an outward flange 188. An air directing sleeve 190 surrounds

the cylindrical part 186 and is secured to the cone 184. The sleeve 190 is turned inward over flange 188 and has a row of holes 192. An imperforate inverted funnel 194 is seated on the edge of the perforated cone 184 and surrounds the latter. The funnel 194 has a ledge or rim 196 (see Fig. 2) which projects downward and has three equally spaced tangs 198 projecting inward. The flange 180 is cut away at corresponding places to permit the funnel 194 to be moved downward without the tangs 198 striking the flange. The rim 196 is cut away at an angle to form a cam portion, not shown, adjacent each cut away portion. When the funnel 194 is to be placed on flange 180, it is first seated and then rotated clockwise so that each of the tangs 198 engages a corresponding cam portion of rim 196 to hold both the cone 184 and inverted funnel 194 in place. A flue supporting sleeve 200 (also see Fig. 1) having three outwardly projecting pins 202 is secured to the base of the inverted funnel 194. The pins 202 project through inclined slots in a flue bracket 204 (Fig. 2) which has a flange for supporting a flue 110. A handle 206 is provided to turn the flue bracket to raise and lower the flue, this action being due to the inclination of the slots with respect to the pins engaged therein.

An inner chimney 114 is located concentrically 30 within the outer chimney assembly 112 (Fig. 1). As best seen in Fig. 2, the inner chimney 114 has four slots extending upward from its lower edge forming four legs 168. These legs project through the four holes 171 in the base plate 158 and are 35 secured to the disc portion 166 of the base plate. The top of the inner chimney 114 is fitted with a perforated cap 116.

A wick assembly 118 is located between the outer chimney assembly 112 and the inner chimney 114. The wick assembly 118 comprises a holder formed by an inner sleeve 122 and an outer sleeve 124 between which is located a cylindrical wick 120. The wick sleeves 122 and 124 are formed with four slots which extend upward from the bottom edges of these sleeves. The sleeves are connected at the peripheries of these slots by inverted U-shaped members 140.

The cylindrical wick 120 has four depending strips or tails, each of which projects downward 50 through a corresponding opening in the lower part of the wick holder. The lower part of the sleeve 124 has a flange 128 at its upper edge, and the upper part 126 of this sleeve rests upon the flange 128 through a pair of bracket clips 130. 55 As seen in Fig. 2, each clip 130 is riveted to the

upper sleeve part 126 and has a horizontal portion 132 which rests on the flange 128, and a downturned part 134. The flange 128 is cut away to form a cam portion 136, and when the brackets 130 are located over the narrowest parts of these cams, the sleeve part 126 may be moved downward into place and then turned clockwise to the position shown in Fig. 1, in which the clips 130 engage the flange 128 and hold the upper sleeve part 126 on the lower sleeve part 124. The annular wick holder which has just been described is provided with a turner for moving the wick vertically therein to adjust the exposure of the wick at the upper edge of the holder. The wick turner will now be described. A bracket 142 is riveted to the inner surface of the wick holder sleeve 124 (Fig. 3). The bracket 142 mounts a guide or sleeve 143 (Fig. 2). The bracket 142 holds a pinion 144 which meshes with a rack 146 which projects downwards through the guide or sleeve 143. The sleeve holds the rack 146 in vertical alignment, and rotation of the pinion 142 moves the rack 146 up and down.

A U-shaped wick clamp 148 is secured to the upper end of the rack 146. The clamp 148 is of resilient material and at its ends is provided with barbed grips 150 for engaging the cylindrical wick 120. The pinion 144 (Fig. 2) has a stub shaft 151 provided with an axial slot at its outer end. A removable key 152 engages in the slot to turn the shaft 151 and the pinion 144. The key 152 has a sleeve 154 provided with a flared end to guide the key into engagement with the pinion shaft 151. By turning the key 152, the pinion 144 is rotated to move the rack 146 up or down, and the wick 120, which is clamped to the rack 146, is likewise moved up or down. When not in use, the key 152 is disconnected from the pinion shaft 151 and dangles on a chain 155 (Fig. 3).

The annular wick holder with its cylindrical wick and wick turner, as previously described, is vertically movable as a unit in the annular space between the inner chimney 114 and the outer chimney assembly 112. Mechanism is provided for causing this movement. This mechanism consists of means such as a spring to urge the wick unit upward, and a device for moving the unit downward against the action of such means.

The wick assembly or unit is urged upward by a helical spring 220. The bottom end of this spring is secured to the disc portion 166 of the base plate 158. The upper end of the spring engages a spider 222 having four ends which project through the slots in the inner flue 114 and bear upward against the inverted U-shaped members 140 of the wick unit. The upper ends of the slots in the flue 114 act as stops to limit the upward movement of the spider 222 and the wick assembly unit. When the latter is pushed downward, the spider is likewise pushed downward and compresses the spring 220.

Referring to Fig. 2, soldered to the lower side of the base plate 158 and concentric therewith is a downward projecting sleeve 172. The latter has a flange at its top edge which is covered by a ring 174. The latter, as shown in Figs. 1 and 3, is provided with integral supporting brackets 176. At the right of the burner there is an adjustable bracket 175 which has a slot 177 through which projects a screw 178 threaded into the casting 156. The device for moving the wick assembly downward against the action of spring 220 in-

cludes a bifurcated lever having arms 208 and a stem portion 210. The ends of the arm portions 208 rest upon two brackets 204 (Fig. 1) which are fastened to the opposite sides of the outer wick sleeve 124. The end of lever 210 is turned downward and formed with a knife edge 212 which pivotally rests in a groove 214 in a frame structure arm 216. The latter is provided with a pair of posts 218 on opposite sides of the lever 210 to guide the latter in vertical alignment. When the lever 210 is pressed downward, as by the thermostat to be described, it pivots about the knife edge 212 and moves the wick assembly downward. The extent of downward movement is limited by contact of the brackets 204 with the base plate 158. Referring to Fig. 1, the casting 156 has a mounting plate 224 consisting of a main portion and a supporting bar portion 228. As best seen in Fig. 2, the bar portion 228 fits on the top of two ledges 230 projecting from the casting 156 at each end of the bar portion. Each of the ledges 230 has a post 232 which projects through corresponding holes in the bar portion 228, and is provided at the upper surface of the bar portion with a latching groove 234. Slidably mounted on the top surface of the bar portion 228 is a latch member 236 (Fig. 3) which has at one end a tab 238, as shown in broken lines in Fig. 2. The latch 236 is held in place by a pair of pins 240 (Fig. 3) which project through an elongated slot 242 in the latch member and into the bar portion 228. The latch member 236 is provided at each end with a keyhole slot 244, the large portion of which receives the end of the post 232, and the narrow end of which snugly fits the post at the latching groove 234 (Fig. 2). In assembly, the bar portion 228 is located with its two holes over the two posts 232, with the latch member 236 having the large portions of the latching slots opposite the holes. The bar is moved downward so that the posts enter the holes and the latch member is then slid by means of its tab 238 to the latched position shown in Fig. 3. The latch member 236 is of resilient material, and it is shaped with an upward bend at its center so that it tends to remain latched.

Referring again to Fig. 1, extending outwardly from the top of mounting plate 224 is a pivot post 246, and at the bottom of the plate is a rigid post 250. Pivotally carried by pivot post 246 is a channel lever 252 which hangs from a set screw 254 with the set screw extending through a pair of ears 256 integral with the upper end of the channel lever. At the bottom, channel lever 252 carries an operating roller 258 and a stop bar 260 which are loosely mounted at their ends to rotate freely. Operating roller 258 is formed by a sleeve loosely carried by an axle pin. Mounted below roller 258 and bar 260, upon a post 262 which is integral with mounting plate 224, is a crank arm 264 which has a horizontal lever portion 266 and a vertical lever portion 268. Lever portion 268 extends between roller 258 and bar 260 and is loosely received therebetween so that it may be freely engaged, and lever portion 266 rests upon the top of stem portion 210 of lever 206. Directly over roller 258 and bar 260 is a coil spring 270 (which is broken away in Fig. 1) which has one end carried by a spring cap 272 the center of which rests against channel lever 252. Spring 270 is held in position in a manner best shown in Fig. 3, there being an integral bracket 274 extending outwardly from mounting plate 224 which carries an adjusting shaft 276. Adjusting shaft 276 is rotatable and is provided at

its outer end with an adjusting knob 278 which carries suitable indicia, as shown in Fig. 2. At the inner end of shaft 276 (Fig. 3) is a threaded portion 280, and this threaded portion receives an adjusting nut 282 against which the end of spring 270 rests. Parallel to shaft 276 and extending from mounting plate 224 is a horizontal, integral ledge 281, and the edge of this ledge extends into a groove (not shown) in the side of nut 282. This ledge prevents rotation of the nut with the result that when shaft 276 is rotated, the thread engagement moves the nut axially along the shaft. In this manner the turning of knob 278 changes the position of the end of spring 270 and consequently changes the pressure exerted by the spring against channel lever 252.

Positioned to engage the side of channel lever 252 opposite spring 270, so as to oppose the action of the spring, is a bellows 284 which is rigidly mounted at the end opposite the channel lever on a bracket 286 integral with mounting plate 224. For purposes of mounting, the bellows is provided with a stud extension 288 which extends through a hole in bracket 286 and receives a nut 290, and bracket 286 is tightly clamped between the base of the bellows and the nut. Capillary tube 102 extends from the outer end of stud 288 and is supported by a rigid arm 293 which is mounted upon bracket 286. The hole in bracket 286 through which stud 288 extends has opening into it a horizontal slot (see Fig. 1) 292, and when it is desirable to remove the bellows, nut 290 is removed and stud 288 is slipped longitudinally out of its hole. The capillary tube may then be slipped outwardly through slot 292. Channel lever 252 is provided with a downwardly extending stop tab 294, and post 250 carries an adjustable stop pin 296 (shown in broken lines in Fig. 3) which is held in adjusted position by means of a lock nut 298. When being installed stop pin 296 is adjusted to provide a proper limit for the swinging movement of the channel lever. After assembly, a cover box 300 (see Fig. 2) is slipped in position with its edge being received in a rabbet (see Fig. 1) 302 along the periphery of mounting plate 224. Cover box 300 is held in place by a thumb screw 304 which is threaded into a hole in the end of post 250.

In use, the gas pressure within bellows 284 depends upon the temperature of thermostat bulb 100. As the temperature of thermostat bulb 100 increases, bellows 284 tends to expand, swinging channel lever 252 against the action of spring 270. This swings bell crank 264 and lifts the lever portion 266 upwardly with the result that lever 206 is permitted to rise, and the wick assembly is lifted by spring 220 (Fig. 2). This exposes additional wick above the chimney and flue assemblies, and the flame is thereby increased. Conversely, when bulb 100 is cooled, bellows 284 tends to contract, and spring 270 swings channel lever 252 with the result that the wick assembly is moved downwardly and the flame is reduced. When adjusting knob 278 is rotated clockwise (Fig. 2), the tension on spring 270 is increased with the result that for a given temperature of the thermostat bulb, a smaller flame will be maintained. With other conditions constant, counterclockwise movement of adjusting knob 278 causes an increase in the flame. Suitable stops (not shown) are provided to limit the rotation of adjusting knob 278.

Various changes may be made within the scope of the invention as set forth in the following claims.

I claim:

5. In a wick type oil burner, an inner chimney and an outer chimney having an annular space therebetween, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, said chimneys having perforated portions for supply of air to a combustion zone in the upper part of said annular space, and mechanism operable to move said assembly up and down relative to said chimneys to regulate the heat of the burner flame.
10. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
15. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
20. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
25. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
30. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
35. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
40. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, means located within said inner chimney operative to urge said unit in one direction, and a device operable to move said unit in the opposite direction against the action of said means and thereby regulate the heat of the burner flame.
45. In a wick type oil burner, an inner chimney and an outer chimney having an annular space therebetween, said chimneys having perforated portions for supply of air to a combustion zone in the upper part of said annular space, concentric cylindrical sleeves secured together in spaced apart relation and forming an annular wick holder, an annular wick in said holder, a turner on said holder for moving the wick vertically therein to adjust the exposure of the wick at the upper edge of the holder, said holder, wick, and turner forming a wick assembly located in and vertically movable as a unit in the annular space between said inner and outer chimneys, said outer chimney having an opening for access to said turner, said inner chimney having vertical slots in the lower part thereof, a spring within said inner chimney connected by projections through said slots to urge said unit upward, and a member operable to move said unit downward against the action of said spring to regulate the heat of the burner flame.
50. In a wick type oil burner as set forth in claim 1 in which said device is thermostatically operated.
55. In a wick type oil burner as set forth in claim 3 in which said member is a lever having a forked end connected to the outside of said holder at diametrically opposite points.
60. In a wick type oil burner as set forth in claim 3 in which said member is a lever having a forked end connected to the outside of said holder at diametrically opposite points.
65. In a wick type oil burner as set forth in claim 3 in which said member is a lever having a forked end connected to the outside of said holder at diametrically opposite points.
70. In a wick type oil burner as set forth in claim 3 in which said member is a lever having a forked end connected to the outside of said holder at diametrically opposite points.

HARRY C. SHAGALOFF.
